(57) **CLAIM**

The ornamental design for a glue gun, as shown and described.

DESCRIPTION

FIG. 1 is a front top left perspective view of a glue gun in accordance with the present invention.

FIG. 2 is a rear bottom right perspective view showing the glue gun of FIG. 1.

FIG. 3 is a left elevation view showing the glue gun of FIG. 1, with the right being a mirror image thereof.

FIG. 4 is a front elevation view showing the glue gun of FIG. 1.

FIG. 5 is a rear elevation view showing the glue gun of FIG. 1.

FIG. 6 is a top plan view showing the glue gun of FIG. 1.

FIG. 7 is a bottom plan view showing the glue gun of FIG. 1.

FIG. 8 is a front top left perspective view showing the glue gun of FIG. 1 with a glue bottle located in the chamber of the glue gun; and,

FIG. 9 is a perspective view showing the glue gun of FIG. 1 with a glue bottle located in the chamber of the glue gun and the glue gun placed in a stand.

The broken line showings of the glue bottle in FIGS. 8 and 9, and the stand in FIG. 9 are provided for purposes of environment, and form no part of the claimed design. The aspects of the glue gun depicted by broken lines and surrounded by dash dot dash lines, form no part of the claimed design.
